UNITED STATES PATENT OFFICE.

ALFRED A. EPPERT, OF AMELIA, OHIO.

MAIL-BAG.

SPECIFICATION forming part of Letters Patent No. 374,735, dated December 13, 1887.

Application filed November 4, 1887. Serial No. 254,271. (No model.)

To all whom it may concern:

Be it known that I, ALFRED A. EPPERT, a resident of the town of Amelia, Clermont county, State of Ohio, have invented certain new and useful Improvements in Mail-Bags, of which the following is a specification.

The object of my invention is to provide a locking device to be attached on the inside of a mail-bag, to lock automatically, and to dispense with the use of straps and padlocks, and thus save much valuable time.

In the accompanying drawings, Figure 1 is a view in elevation of the top portion of a bag and flap with my improved locking device attached thereto, the outer upper portion of the bag and the shield being broken away to show said locking device. Fig. 2 is a vertical cross-section of the top portion of a bag provided with the locking device, the said parts being in position just before locking. Fig. 3 is a view similar to Fig. 2, showing the bag locked. Fig. 4 is a top view of the locking-bolt, plate, and spring to be attached to the inside of the flap of the bag, as shown in Fig. 1. Fig. 5 is a side elevation of the plate shown in Fig. 4, showing the manner of attaching the spring thereto. Fig. 6 is a vertical cross-section taken through one of the lock-cases, showing the preferred form and construction of the locking-jaws. Fig. 7 is a side elevation of one of the lock-cases, showing the circular slot in which the pin attached to the locking-jaws operates. Fig. 8 is a side elevation of four of my improved lock-cases and hinged plates and connecting operating mechanism as preferably constructed.

My invention is applicable to any of the ordinary mail-bags now in use, and is preferably constructed in the following manner: To the inner top portion of the back of the bag is riveted or suitably secured a series of plates, A, which are pivoted or hinged together, as shown in Figs. 1, 7, and 8, to allow the bag to be doubled on itself, and also to keep the locking-jaws an equal distance apart. If attached to the leather, these jaws would vary, as the leather would expand when dampened and contract when dried out. This series of hinged plates entirely overcomes this difficulty. As shown, and as preferably constructed, to each alternate plate is attached, in any suitable man-

ner, one of the lock-cases B, in which the jaws b are secured and pivoted in the usual manner.

Around each of the pivots is coiled a spring- 55 wire, b', one end of which is secured to the case and the other end to the jaw, as shown in Fig. 6. These jaws b may be secured in locking position by any suitable spring mechanism, the object being to constantly keep the 60 jaws locked until separated in the manner presently to be described.

To each of the jaws b is secured a pin, b², which latter projects through the case, (one on either side,) as shown in Figs. 7 and 8. These 65 jaws b are inclined inward and downward on their upper face at an angle to receive the angular-shaped bolt C and to permit said bolt being pressed in between the jaws and separating them. The jaws are again brought back 70 into locking position so soon as the flanged portions of bolt C have passed the flanged portion of said jaws by means of the springs b'.

Having now described the construction of the hinged plates, lock-cases, and jaws, I will 75 briefly describe the construction of the mechanism for unlocking the jaws.

To the outer end of each of the end plates is (when constructed as shown) pivoted the lever D, to each end of which the chain or 80 strap d is attached, as shown in Fig. 8. One end of this chain or strap is attached to a pin or lug, d', made fast, preferably, to the center connecting-plate, the other end of said chain being attached to the lever. One end of the 85 adjacent reciprocal chain or strap is attached to a lug or pin, d'', made fast to the tumbler D', the other end being attached to the lever. Near the stationary pins d' the chain has a link of coiled spring, d³, to assist in bringing 90 the parts back into locking position, as will hereinafter appear.

The pins b², attached to the jaws b, extend through the openings in the lock-cases, as shown in Fig. 7, to which pins the chains or 95 straps d are made fast, as shown in Fig. 8. When the tumbler D' is made to rotate from left to right by means of any suitable key, the top chains (when constructed as shown in Fig. 8) are drawn to the right and the lower chains 100 or straps are drawn to the left. The pins b², being connected to the chains or straps, will

necessarily move to the right and left as the chains are moved, and, said pins being connected to the jaws, this right-and-left movement of the chains and pins will cause the 5 jaws *b* to open or separate to allow the flanged portions of the bolt to escape from said jaws.

Instead of using the levers *D* at each end, as shown, two covered pulleys may be employed, the chain or strap at either end passing over said pulleys instead of being attached to each end of the levers, as shown. This series of hinged plates, locks, and operating mechanism is preferably covered with a shield, *E*, which may be made of leather or other 15 suitable material and riveted or otherwise suitably secured to the bag, as shown in Figs. 2 and 3.

The plate *F*, to which the locking-bolt *C* is attached, is secured to the inside of the flap 20 by any suitable means. These plates *F* may be connected by hinged connecting plates to correspond with the plates *A*. To the inner side of this plate *F* is preferably secured a flat spring or equivalent, *G*, in any desired manner. Through an opening in this spring the bolt *C* passes, as shown in Figs. 4 and 5, the object of the spring *G* being to cause the flap to open when the bolt *C* is released from the jaws *b*, in the manner before described. The locking-bolts *C* pass through suitable openings, *H*, 25 in the front face of the bag and corresponding openings in the shield and cases, as shown in Figs. 2 and 3. When locked, the tendency of this spring *G* is to cause the flanges on bolt *C* to bear against the flanged portion of the jaws *b*, and so soon as these jaws are separated by rotating the tumbler *D'* the flap is made to fly 30 open through the resiliency of the spring *G*. This tumbler *D'* is covered with a suitable escutcheon, in the usual manner, and is rotated by a key inserted through a suitable opening in the flap of the bag, as shown in Fig. 1. But one tumbler is necessary to operate two or more 35 of said locking devices. When the bag is locked, there is nothing visible from the outside, excepting the heads of the bolts or rivets and the key-hole.

The advantages of my device are apparent. Besides being cheap of manufacture and simple in construction and operation, the bag cannot 50 be unlocked, except by use of the key. Much time is saved by the use of my invention, as no straps or padlocks are used to take up time in locking and unlocking the bag. To lock the bag, all that is required is simply to press 55 the flap on the bag, the locking being accomplished automatically. To unlock the bag, the tumbler is rotated by means of the key, thus unlocking the bag in a second of time.

What I claim as new, and desire to secure 60 by Letters Patent, is—

1. In a lock for mail-bags, a series of metallic cases containing suitable locking-jaws, said cases being connected by the hinged plates secured to the inside of the bag, and mechanism 65 consisting of suitable chains attached to a tumbler and connecting-pins for simultaneously unlocking all the jaws, the whole being covered with a shield, in combination with locking-bolts attached to the inside of the flap of 70 the bag, substantially as set forth.

2. In a lock for mail-bags, the flanged bolts *C*, springs *G*, and plates *F*, attached to the inside of the flap, in combination with a series of locking-jaws secured to the inside of the 75 bag, and suitable chains connected to said jaws, and mechanism, substantially as described, for operating said chains, as and for the purposes set forth.

3. In a lock for mail-bags, a series of metallic casings, *B*, having the jaws *b* secured therein, connecting-plates *A*, springs *b'*, for keeping the jaws locked, chains *d*, attached to tumbler *D'* and to levers *D* or equivalent devices, pins *b'*, attached to the jaws *b* and to said chains, 85 and shield *E*, in combination with bolts *C*, substantially as set forth.

ALFRED A. EPPERT.
